UNITED STATES PATENT OFFICE

HENRY HAUBENS AND LAMBERT H. HOLCOMB, OF OMAHA, NEBRASKA

WASHING MACHINE

Application filed September 15, 1930. Serial No. 481,911.

Our invention relates to washing machines of the class wherein a tub or container for the cleansing fluid is mounted pivotally upon a horizontal axis, about which the container is oscillated to agitate the contents, the container being shaped to effect a transverse surging and swirling of the cleansing fluid to force the same through and about the articles immersed therein for washing. It is the general object of our invention to provide in a washing machine of this class certain refinements and improved structures adapting the same for use by commercial laundries and dry cleaners, for wet washing and dry cleaning, under either batch or continuous-flow modes of operation. Particular objects of our invention are to provide, in a washing machine of this class, means for supplying the cleansing fluid to the tub or container while the same is in motion, and for directing the fresh fluid either to the bottom of the tub or upon the contents thereof from above the same, as may be desired; to provide means whereby the cleansing fluid may be withdrawn from the container while the same is in motion, either to completely drain and discharge the fluid content or to continuously withdraw portions thereof as fresh fluid is supplied; to provide means whereby insoluble or sedimentitious particles of material are withdrawn from the main body of the cleansing fluid during the washing operation, and retained in a separate drainable compartment, for intermittent discharge as may be desired; to provide for the container doors or hinged covers which are normally held in closed position and which may be opened and held open during the operation of the washer to enable inspection of the contents; and to so form the oscillating tub as to provide a maximum agitation and relative movement of the cleansing fluid and articles immersed therein, without liability of splashing or throwing the fluid through the top opening of the tub when the doors are open.

In the accompanying drawings Fig. 1 is an end elevation of a machine embodying our invention, and Fig. 2 is a longitudinal vertical section of the same on the line 2—2 of Fig. 1.

In carrying out the invention according to the illustrated embodiment thereof, we provide a frame having similar end-members, each comprising a central annular portion 5, having integral leg-portions 6 extending to the front and rear from the lower part thereof, and having an integral standard 7 extending from the upper portion thereof and provided at its upper end with a bearing 8. Said frame end-members are rigidly connected and held in spaced parallel relation by a semi-cylindrical longitudinal member 9, extending between the upper parts of the annular portions 5, and having flanged ends bolted thereto. At the centers of the annular portions 5 are bearings 10 for the main longitudinal shaft 11 which carries at one end a gear 12. Meshing with said gear is a suitable pinion 13, carried by a drive-shaft 14 having one end journaled in the end frame-member and the other end journaled in a bracket 15 attached to the frame, as shown. On the shaft 14 are tight and loose pulleys 16 and 17, adapted to be driven by belt from a suitable source of power, the upper portion of the bracket 15 carrying a belt-shifting device 18 for guiding the belt onto the tight or loose pulley as required. The pinion 13 and gear 12 are inclosed peripherally by the annular portion of the frame-member, and are shrouded or partially inclosed at the outer side by a guard-plate 19 secured to the frame-member by screws 20. On the shaft 14, at the end thereof opposite the gear 12 and inclosed by the annular portion of the respective end frame-member, is a disk or crank-plate 21. Crank-pins 23, arranged in axially aligned relation on said plate 21 and the gear 12, are connected with the lower ends of pitmen 22 which extend upward therefrom and have their upper ends connected with the oscillating tub, as hereinafter described, for actuating the same.

The oscillating tub has substantially flat parallel end-plates 24 and 25, flanged outwardly at the edges thereof, which are of similar contour, and said contoured edges of each end-plate are symmetrical to a central vertical longitudinal plane, as shown. Each side of the tub-body is inclosed by an inte-

gral sheet of metal of which the end portions overlap the flanges of the contoured edges of the end-plates and are secured thereto by suitable rivets. The side-sheets of the tub-body thus conform throughout their length with the contoured edges of the end-plates, and provide a slightly concave central bottom portion 26, steps 27 extending upwardly and slightly inclined outwardly 5 from the sides of the bottom portion 28, shelf portions 28 having a slight upward inclination and extending outwardly from the steps 27, steps 29 inclined inwardly and extending up from the sides of the shelf portions 28, 10 divergent inclined portions 30 extending upwardly and outwardly from the steps 29, and shoulder portions 31 extending upwardly from the upper edges of the portions 30, said shoulder portions 31 curving inwardly and 15 slightly downward at their inner edges. At said inner edges of the shoulder portions are longitudinally extending angle-bars 32, which form the sides of the top-opening of the tub. Said top-opening is rectangular 20 and continuous from one end-plate to the other, except that there is a central transverse bar 33 lying between the adjoining ends of the cover-plates or doors 35 and 36, which are connected with the tub-body at the rear 25 side of the top-opening by suitable hinges 37. The form of the tub-chamber as a whole is thus prismoid and symmetrical to a vertical longitudinal plane, the lower portion being stepped and inclined toward the plane 30 of symmetry, and the upper portion, formed by the shoulders 31, having a reentrant curvature. The tub is supported by tubular trunnions 38 journaled in the bearings 8 and having their inner ends affixed in bosses or nipples 39 formed integrally with the end-plates 24 and 25 centrally thereof. On the end-plates, slightly below and rearward of the trunnions, are axially alined pins or studs 40 to which are connected the upper ends of the 35 pitmen 22, whereby during rotation of the main shaft 11 the tub is oscillated about the trunnion-axis, the driving force being thus imparted equally to both ends of the tub, and torsional stresses in the tub and frame being 40 avoided.

The tubular trunnions 38 project through the bearings 8, and the outer end of each extends into a T-cap 41 secured to the outer end of the respective bearing. A packing-gland 42 is provided at the inner end of each T-cap, to form a fluid-tight joint about the tubular trunnion, and at the outer end of the cap is a removable plug 43, which provides access to the gland for re-packing thereof. The side- 45 openings of the T-caps are threaded for connection with pipes 44 and 45, through which the cleansing fluid may be supplied to or withdrawn from the tub. In the structure shown, the inner end of the tubular trunnion on the end-plate 25 communicates with a passage

46 formed within said plate, extending downwardly from the trunnion and opening into the lower portion of the tub-chamber, the opening being covered by a suitable screen 47. Formed within the end-plate 24 is a passage 48 communicating with the respective tubular trunnion and extending upwardly therefrom, as shown. The upper end of said passage 48 normally communicates with a perforate tube 49 carried by the door or cover-plate 35, said tube 49 having a diagonal end-face which rests against the end-plate to form a joint about the outlet of the passage 48 when the door is in normal closed position. Spray-pipes 50 may also be fixedly connected with the end-plate 24 to communicate with the passage 48 and extend longitudinally within the upper portion of the tub-chamber, at the sides of the top-opening thereof. In some cases, as where the machine is to be used exclusively for dry cleaning, it is desirable that the fluid-passages from the tubular trunnions be extended to the bottom of the tub at both ends, similarly to the passage 46 of the end-plate 25. In other cases, as where the machine is to be used exclusively for wet washing, it is desirable that the fluid-passages from the trunnions at both ends of the tub be extended to the upper portion of the tub-chamber, to connect with spraying means such as the perforate tube 49 or spray-pipes 50.

In the lower portion of the tub is a central longitudinally extending perforate false bottom plate 51, beneath which is formed a narrow longitudinally extending chamber 52. The bottom of the chamber 52 is downwardly inclined from the ends toward the center of the tub, at which there is a drain or discharge-opening which is normally closed by a hinged valve-plate 53. A shaft 54 is connected with the valve-plate 53, and extends longitudinally past one end of the tub. At the end of said shaft 54 is a crank-arm 55 from which a rod 56 is extended upwardly to connect with a crank-pin 57 on a crank-plate 58 mounted pivotally on a pin 59 on the end-plate 25. The crank-plate 58 has a handle 60 for convenience in turning the same, and the edge of the plate is notched to receive a stop-lug 61 for limiting movement of the plate about the pin 59. At the position shown in Fig. 1, the crank-pin 57 is substantially on dead-center, or alined with the rod 56 and the pivot-pin 59, and the valve-plate 53 is retained in closed position. By pulling forwardly upon the handle 60, to move the crank-plate until the opposite end of the notch therein engages the stop-lug 61, the rod 56 is pulled upwardly and the valve-plate is swung to open position. A reverse movement of the handle 60 will close the valve, and either the opening or closing movement may be readily effected while the machine is in

operation and the tub is oscillating about its trunnion-axis.

Beneath the tub, resting upon and secured to the longitudinal frame-member 9, is a drain-pan 62 having formed integrally therewith, at the central rearward portion thereof, a spout 63 extending somewhat above the rear edge of the pan, and extending down around the rear side of the frame-member 9.

- 10 The lower end of said spout 63 is adapted to discharge into a suitable sewer connection the liquid which drips or is discharged into the pan 62, and the extent of the pan is such as to receive from the tub any liquid drained 70 or discharged therefrom, either while the same is in motion or held stationary at any position to which it may be actuated by the pitmen 22.

Each of the doors 35 and 36 is provided 20 with controlling means consisting of a lug 65 extending over the edge of the adjacent end-plate, a link 66 connected pivotally with said lug 65, and a lever 67 having said link 66 connected pivotally with an intermediate portion 25 thereof, the rear end of said lever being pivotally connected with a lug 68 on the adjacent end-plate, and the front end of the lever having a knob or handle 69 for convenience in grasping the same. When the 30 door is in normal closed position the members of the controlling device are positioned as shown in Fig. 1, and the weight of the lever 67 and knob 69 tends to hold the door closed. The door is opened by moving the knob 69 up- 35 wardly to swing the lever to the position indicated by dotted lines in Fig. 1, at which the lever is alined with the link 66, and the upper portion rests against the end of the lug 65. Movement of the door-control-lever is 40 readily effected during the oscillating movement of the tub, the door-opening movement being made while the upper portion of the tub is moving forwardly, and the closing movement being made while the upper portion 45 of the tub is moving rearwardly. The control devices serve to retain the doors in either open or closed position during the oscillating movements of the tub about its trunnion-axis.

50 In the operation of the machine, the tub is normally filled with the desired cleansing fluid to a level slightly below the trunnion-axis. During the oscillating motion of the tub about said axis, the fluid is caused to 55 surge from side to side, the articles to be washed being submerged in the cleansing fluid and, because of the stepped formation of the bottom portion of the tub, being restrained from moving freely with the fluid, so that 60 the latter is caused to flow through and about the articles. Also, at the limits of the oscillating movements, when the direction of motion is reversed, the surging fluid is deflected by the curved shoulder portions 31 of the 65 upper portion of the tub-body, and directed

inwardly and downwardly, so as to descend forcibly upon the articles in the lower portion of the tub-chamber. The reentrant curvature of the shoulder portions, by directing the fluid downwardly, enables the doors to be opened for inspection of the work while the tub is in motion, without liability of the fluid being thrown or splashed out through the open top of the tub.

Ordinarily, the cleansing fluid is supplied 70 from the pipe 44, through the passage 48, tube 49 and pipes 50, being thereby sprayed onto the load or contents of the tub. For ordinary laundry purposes in which water is employed for the washing, the spraying 75 of the water onto the dry articles, after the same are placed in the tub and while the tub is in motion, causes a rapid "breakdown" of initial wetting of the articles; and after the initial washing operations are completed 80 the rinsing of the load is greatly facilitated by the spraying of the rinse-water thereon while the load is agitated by the motion of the tub. For batch operation, the supply 85 of water is stopped after the tub has been filled to the desired level, and after the desired period of agitation the drain-valve 53 is opened, allowing the water to be discharged into the drain-pan 62 and spout 63, without stopping the oscillating motion of 90 the tub. After the water has been drained from the tub, the valve 53 is closed, the tub again filled, with the desired solution for the next washing operation, agitation continued for the desired time, the liquid drained 95 off as before, the re-filling, agitation, and draining being repeated as often as may be necessary to effect the washing and rinsing of the load, and the motion of the tub need not be stopped until the rinsed and drained 100 load is ready for removal from the tub. During the washing operations, insoluble and sedimentitious material tends to pass through the perforate bottom-plate 51 into the chamber 52, and to be retained therein until released by opening of the drain-valve 53, so that the greater portion of such materials 105 are removed from the active liquid in the main body of the tub, instead of being retained therein until the final draining and 110 rinsing operations.

For continuous-flow operation, portions of the liquid may be constantly withdrawn from the tub through the pipe 45, from the passage 46, through the screen 47 at the opening 115 to said passage, and the drain-valve 53 opened intermittently and for a sufficient time only to effect the discharge of sediment from the chamber 52.

Now, having described our invention, what 120 we claim and desire to secure by Letters Patent is:

1. In a washing machine, a tub-body having vertical end-plates and shaped to inclose a prismoid chamber symmetrical to a 125

vertical longitudinal plane, trunnions affixed to said end-plates and alined axially in said plane of symmetry intermediate the upper and lower portions of the tub-body, a frame having bearings supporting said trunnions, means for oscillating the tub-body about the trunnion-axis, the oscillating tub-body having at the bottom thereof a longitudinally extending sediment-chamber, a perforate plate covering said sediment-chamber and affording communication with the main tub-chamber throughout the length thereof, said sediment-chamber having a drain-opening, a valve controlling said drain-opening, and an actuating-member connected with said valve and mounted upon an end-plate of the tub-body adjacent to the trunnion-axis and movable in the plane of oscillation to open and close the valve.

2. A washing machine comprising a tub-body inclosing a prismoid chamber shaped symmetrically to a vertical longitudinal plane and having vertical end-plates, tubular trunnions affixed to said end-plates and alined axially in said plane of symmetry, a frame having bearings supporting said trunnions, means for oscillating the tub-body about the trunnion-axis, pipes carried by the frame and connected with the outer ends of the tubular trunnions, the end-plates of the tub-body having passages therein communicating with the passages through said trunnions and connecting the same with the tub-chamber, liquid-spraying means arranged in the upper portion of the tub-chamber and connected with the passage through the end-plate from one of the tubular trunnions, the bottom of the tub-body having a drain-opening therein, and a valve controlling said drain-opening.

3. A washing machine comprising a tub-body inclosing a prismoid chamber shaped symmetrically to a vertical longitudinal plane and having vertical end-plates, tubular trunnions affixed to said end-plates and alined axially in said plane of symmetry, a frame having bearings supporting said trunnions, means for oscillating the tub-body about the trunnion-axis, pipes carried by the frame and connected with the outer ends of the tubular trunnions, the end-plates of the tub-body having passages therein communicating with the passages through said trunnions and connecting the same with the tub-chamber, the passage through one of the end-plates extending to the lower portion of the tub-chamber whereby liquid may be withdrawn therefrom through said passage and the respective trunnion simultaneously with the supplying of liquid to the tub-chamber through the other trunnion.

4. In a washing machine, a tub-body having vertical end-plates and shaped to inclose a prismoid chamber symmetrical to a vertical longitudinal plane, trunnions affixed to said

end-plates and alined axially in said plane of symmetry intermediate the top and body of the tub-body, a frame having bearings supporting said trunnions, means for oscillating the tub-body about the trunnion-axis, the tub-body having a drain-opening in the bottom thereof, a valve controlling said drain-opening, and an actuating member connected with said valve and mounted upon an end-plate of the tub-body adjacent to the trunnion-axis, said valve-actuating member being movable relative to said end-plate in a plane parallel therewith to open and close the valve during the oscillating motion of the tub-body.

5. A washing machine comprising a tub-body inclosing a prismoid chamber shaped symmetrically to a vertical longitudinal plane and having vertical end-plates, tubular trunnions affixed to said end-plates and alined axially in said plane of symmetry, a frame having bearings supporting said trunnions, means for oscillating the tub-body about the trunnion-axis, pipes carried by the frame and connected with the outer ends of the tubular trunnions, the end-plates of the tub-body having passages therein communicating with the passages through said trunnions and connecting the same with the tub-chamber, the tub-body having a longitudinally extending opening at the upper side thereof, a hinged door normally closing said opening, and liquid-spraying means carried by said door and in the closed position of the door being in communication with the passage through an adjoining end-plate to receive liquid therefrom.
